(57) CLAIM

The ornamental design for an edge protector for sanding machine as shown and described.

DESCRIPTION

FIG. 1 is a front top perspective view of an edge protector for sanding machine embodying my design;

FIG. 2 is a bottom perspective view of FIG. 1;

FIG. 3 is a top plan view of FIG. 1;

FIG. 4 is a bottom view of FIG. 1;

FIG. 5 is a front side elevational view of FIG. 1;

FIG. 6 is a back side elevational view of FIG. 1;

FIG. 7 is a right side elevational view of FIG. 1; and,

FIG. 8 is a left side elevational view of FIG. 1.

1 Claim, 6 Drawing SheetsFIG. 1

FIG. 2

FIG. 3

FIG. 4

FIG. 5

FIG. 6

FIG. 7

FIG. 8
